UNITED STATES PATENT OFFICE.

DAVID G. HARDY, OF WASHINGTON, DISTRICT OF COLUMBIA, ASSIGNOR OF ONE-HALF
TO J. ELVANS MAYFIELD, OF WASHINGTON, DISTRICT OF COLUMBIA.

LOCK.

1,360,943.

Specification of Letters Patent. Patented Nov. 30, 1920.

Application filed January 28, 1920. Serial No. 354,533.

To all whom it may concern:

Be it known that I, DAVID G. HARDY, a citizen of the United States, residing at Washington, in the District of Columbia, 5 have invented new and useful Improvements in Locks, of which the following is a specification.

This invention relates to permutation locks and the objects are to provide a lock which 10 consists of relatively few parts which may be cheaply manufactured, which cannot be opened except by manipulation of the combination dial, which is so constructed that the various operating units are secured together, one by the other, and which may 15 be readily dismantled and the combination changed without the use of tools or instruments and in which the new combination may be readily ascertained by the operator. 20 I have illustrated one embodiment of my invention in the accompanying drawings, wherein:

Figure 1 is a perspective view of my improved lock.

Fig. 2 is a perspective of the lock disassembled.

Fig. 3 is a vertical section showing parts of my improved lock in closed position.

Fig. 4 is a vertical section showing parts 30 of the lock in open position.

Fig. 5 is a transverse vertical section.

Fig. 6 is a horizontal section through the lock body.

Fig. 7 is a perspective view of the tumbler 35 barrel.

Fig. 8 is a rear perspective of the dial and dial spindle.

My lock, one embodiment of which I have 40 illustrated in the form of a padlock, but which it is to be understood may be used in other forms, comprises a body portion 1 preferably constructed of a solid body of metal and being centrally drilled through its front face to provide a chamber 2. Apertures 45 3 are provided through the top face of the lock, these apertures extending downward and communicating with chamber 2, in their adjacency to said chamber taking the form of recesses 4.

50 The operating mechanism of my lock comprises a cylindrical barrel 5 having its top side face cut away, as at 6, and provided with an axial inwardly projecting sleeve 7. The lock body is provided with a lug 8 projecting 55 from its lower interior face and

which is adapted to coöperate with a slot 9 formed in the barrel, thus centering the barrel in position within the body. A tumbler disk 10 suitably notched, as at 11, is positioned within the barrel surrounding the 60 sleeve 7. This tumbler disk is formed with a circumferential series of apertures 12, one of which apertures is filled with a removable pin 13 adapted to project rearward from the face of the tumbler. A spacing ring 14, 65 preferably of spring metal, is positioned within the barrel, the ends of said spacing ring projecting into grooves 15 formed in the side walls of the barrel. This ring is adapted to bear against the rear side of 70 tumbler disk 10. A second tumbler disk 16 is provided which likewise has a bearing upon the sleeve 7. This tumbler is provided with a circumferential series of apertures similar to those in disk 10 and has a pin 17 75 adapted to extend through one of said apertures and project from both side faces of the tumbler disk. A spacing ring similar to the one heretofore mentioned is mounted back of this second tumbler disk. A dial 80 member 18 having a spindle 19 adapted to project through sleeve 7 of the barrel is provided, this spindle having a removable cross-pin 20 adjacent its free end through means of which it is secured in position in the barrel, the cross-pin bearing upon the inner 85 edge of sleeve 7 and is adapted to actuate a third tumbler disk or dial tumbler 21 centered upon the dial spindle 19. This third tumbler disk or dial tumbler is provided with a central aperture and is recessed, as at 22, to take over the pin 20, being secured in position in the barrel by means of spring washer 23. The outer face of the barrel 5 is formed with a horizontal recess 24, and in 90 this recess are positioned a spring 25 and a small ball 26. The inner face of the dial member is provided with a circumferential series of recesses 27 adapted to coöperate with the spring-pressed ball to produce a 100 clicking sound when the dial is rotated. The dial is provided with the usual radial marking lines upon the front face thereof and has a milled handle 28 of somewhat circular contour, one side being cut away, as at 29, in 105 order to provide a flat portion by means of which the position of the dial relative to the barrel and body of the lock may be determined without the necessity of viewing the markings upon the dial.

The upper inner wall of the chamber in the body portion is recessed, as indicated at 30, in order to provide a seating for the bolt member which consists of the body portion 31, a pivoted dog 32, and a tongue 33. The bolt member 31 is provided with a spring strip 33^a one end of which bears upon dog 32 to press that member to operative position with the notched tumbler disks. The barrel 10 portion of the lock is provided adjacent its open side 6 with a pin 34 which is adapted to coöperate with the pivoted dog 32 to prevent the bolt from being withdrawn until the notches of the tumbler disks are in alignment and insure when the bolt is being thrown back that the dog remains in operative contact with the notched portions of the tumbler disks.

The channel 3 which is adapted to receive 20 the leg member of the shackle 35 has a pin 36 projecting through its side walls. This pin is adapted to coöperate with the shoulder portion 37 of the shackle in order to secure the shackle in place in the lock body and the 25 shackle has a reduced portion 38 adjacent the shoulder portion, this flat reduced surface providing means whereby the shackle may be turned, pulled upward, and disconnected from the lock body. The shackle is 30 provided with the usual locking notch 39.

The outer side walls of the barrel portion have vertical recesses 40, these recesses being adapted to coöperate with the recessed portions 4 of the body to provide a channel 35 for the reception of the plug member 41, which fits tightly into and is frictionally held in the recess, and the leg end of the shackle, and it will be apparent that when these members have been inserted in the lock, that by 40 reason of the provision of the recessed sides of the barrel member, the barrel and dial will be securely held in place within the lock and cannot be removed until the plug member and shackle have been withdrawn. An 45 opening 42 extends from the bottom of the lock and is in communication with one of the recesses 4 of the lock body whereby a pin or other instrument may be inserted to force the plug 41 from the body. I provide a usual spring 43 in one of the recesses 3 which is adapted to force the leg of the shackle upward when the bolt has been removed from engagement with the shackle notch.

The operation of my device is as follows: 55 Upon rotation of the dial, tumbler disk 21 which is keyed to the dial spindle will be rotated. This tumbler will revolve until the pin projecting from the front face thereof comes in contact with the pin projecting 60 through the second tumbler 16, whereupon it will turn the second tumbler, which, in turn, as its projecting pin meets the pin projecting rearward from the front tumbler may be rotated to a position where its notched 65 portion is in vertical alignment with the piv-

oted dog of the bolt. The dial is then turned in the opposite direction until the second tumbler has taken a similar position to that occupied by the first, whereupon the rotation is again reversed until the third tumbler 70 has its notched portion in alignment, whereupon the pivoted dog will be forced by action of its spring into engagement with the notched portions of the tumblers. The dial is then turned in the opposite direction which 75 results in the withdrawal of the bolt from contact with the shackle. The shackle will then be forced upward by the action of spring 43 in the usual manner. If it is desired to dismantle the lock to change the combination, the shackle member is then turned until the free end has swung away from the lock body, whereupon the shackle may be lifted out. A pin or other instrument may then be inserted into opening 42 to force the 80 plug member 41 from the body, whereupon the dial and barrel members may be withdrawn from the body of the lock. To change the combination, the spring washers 23 and 14 are removed and the pins on the various 85 tumbler disks may be changed and fitted into any of the different apertures. To ascertain the combination prior to putting the lock together again, the tumbler disks are then replaced in position, the spring washers inserted to hold the parts together, and prior to inserting the barrel and tumbler disks in the lock body, the dial may be rotated until the first tumbler comes into vertical alignment with the cut-away portion of the walls 90 of the barrel, the turning movement of the dial is then reversed until the second tumbler has taken position, and the movement is reversed to effect position of the third tumbler. By keeping count of the movements required 95 to effect this alignment, the new combination may be readily ascertained.

Having fully described my invention, I claim—

1. A lock comprising a body portion having a central chamber adapted to receive a lock barrel, said chamber being formed with side wall recesses and a horizontal recess in the upper wall thereof, a slid able bolt in said upper recess, a barrel adapted to fit said chamber, a dial member fitted to said barrel, said dial member being provided with a spindle, a plurality of tumbler disks arranged within said barrel, a shackle, and means whereby when the dial member is rotated said tumbler disks will be turned to operative position relative to said bolt. 110

2. In a lock, a body portion adapted to provide a chamber for the reception of a tumbler barrel, a tumbler barrel having a 115 centrally drilled chamber and recessed outer sides, a sleeve projecting from the inner side of said barrel, a dial face superimposed upon said barrel, a spindle projecting from said dial face through the sleeve of said barrel, 120

130

a plurality of notched tumbler disks mounted in said barrel on said sleeve, a notched tumbler disk mounted on said dial spindle adjacent said first-named tumblers and 5 means whereby when the dial piece is turned in successively opposite directions the notches of said tumbler disks will be moved into alinement, said body portion being formed with openings through the top part 10 thereof for the reception of a shackle, said openings being in communication with recesses in the side walls of said central chamber, the upper wall of said central chamber being formed with a recess, a bolt in said 15 last-named recess, a spring in one of the side recesses of said central chamber, a cylindrical plug member in the other side recess of said central chamber, said plug member being adapted to project on one side into 20 said central chamber and to coöperate with one of the recessed sides of said barrel portion to maintain the barrel in position, the leg portion of said shackle member being adapted to rest in the other recess in the side 25 wall of the central chamber and to coöperate with the other recessed side of the barrel portion to maintain the barrel in position.

3. A lock comprising a body portion provided with a chamber for the reception of 30 a tumbler barrel, a cylindrical barrel portion positioned in the chamber in said body portion, a tumbler disk formed with a plurality of circumferentially arranged holes therethrough and having a removable pin 35 fitted into one of said holes and projecting from one face of the disk, a second tumbler disk formed with a plurality of circumferentially arranged holes therethrough and having a removable pin fitted into one of 40 said holes and projecting from both faces of said disk, a third tumbler disk formed with a plurality of circumferentially arranged holes therethrough and having a removable pin fitted into one of said holes and projecting 45 from one face of said disk, said tumbler disks being mounted in the barrel portion, means for rotating the last-named tumbler disk whereby the pin projecting from said disk will engage the pin projecting from one 50 face of the second-named tumbler disk to turn said disks into operative relation one to the other, a bolt member positioned in said body portion, and means whereby when the tumbler disks have been turned to assume 55 a predetermined relation, the bolt is withdrawn.

4. In a lock, a body portion having a central chamber adapted to receive a tumbler barrel, a shackle operatively disposed relative to said body portion and having its ends housed in said body portion, a sliding bolt adapted to latch one end of said shackle member, a barrel portion formed with vertical recesses in its outer side faces positioned in said body portion, a plurality of 60

notched tumbler disks mounted in said barrel portion, means whereby the rotation of one of said disks will result in rotation of the other disks, the other end of said shackle being adapted to coöperate with one of the 70 recessed sides of said barrel portion to retain the barrel portion and tumbler disks in position in the body portion, and spring washers interposed between each pair of 75 said disks.

5. In a lock, a body portion consisting of a block of metal having a centrally drilled chamber in its front face, a pair of vertical apertures in the upper face of said block, said apertures communicating with the central chamber and assuming in adjacency thereto the form of recesses, a cylindrical barrel having a cut-away portion in its upper side face positioned in said chamber, said barrel portion being formed with vertical recesses in its outer side walls, a shackle having its ends normally positioned in the apertures of said body portion, tumbler disks mounted in said barrel portion, means to actuate said tumbler disks, a sliding bolt positioned in said body portion and adapted under actuation of said tumbler disks to engage one end of said shackle, a plug member positioned in one of said recesses in the chamber of the body portion, said plug and 90 one end of said shackle coöperating with the recessed portions of said chamber and the recessed sides of said barrel to retain the barrel in position in the body portion.

6. In a lock, a body portion having a chamber adapted to receive a tumbler barrel, a lug in the lower inside wall of said central chamber, a tumbler barrel provided with a groove in the lower outer wall thereof, a plurality of tumbler disks carried by said 100 barrel portion, means to rotate said tumbler disks, a bolt member carried by said body portion and means whereby when said tumbler disks have been turned to proper position, the bolt member is actuated.

7. In a lock, a body portion provided with a chamber for the reception of a tumbler barrel, a tumbler barrel, a shackle operatively associated with said body portion, a plurality of notched tumbler disks in said 115 barrel portion, means to rotate said tumbler disks whereby the notched portions may be brought into alinement, a bolt member having a hinged dog slidably mounted in said body portion, a strip spring secured at one 120 end to said bolt member, the free end of said spring bearing upon said hinged dog, said dog being adapted to engage the notched portions of said tumbler disks when they have become alined whereby the bolt is actuated, and a pin projecting from said barrel portion and beneath said strip spring and adapted to prevent sliding movement of the bolt before said dog has engaged the notched portions of said disks.

8. In a lock, a body portion having a central chamber adapted to receive a tumbler barrel, said body portion being provided with a vertical channel through the top face thereof adapted to receive one end of a shackle, the lower portion of said channel taking the form of a recess in the side wall of said central chamber, a second vertical channel through the top face of said body portion adapted to receive a plug member and the latching end of said shackle, the lower portion of said channel taking the form of a recess in the side wall of said central chamber, a shackle, the pivotal end of which is formed with a circumferential shoulder and having its shank cut away on one side adjacent said shoulder to provide a portion having a plane face and of reduced diameter, a pin projecting through said body portion and one side of one of said vertical channels and adapted to coöperate with said shouldered end to retain the shackle in the body portion, a bolt provided with a hinged dog slidably mounted in a recess in the upper wall of said central chamber, a barrel portion having a relatively central chamber and an axial sleeve projecting into said chamber, the inner walls of said chamber being formed with horizontal grooves, and the upper wall portions being cut away so as to provide an opening, a plurality of notched tumbler disks mounted in said barrel portion, a pin projecting inwardly from said barrel portion in the opening in the upper walls, said pin being adapted to hold the bolt actuating dog in position in the notches of said tumbler disks while the dial is being turned to release the bolt.
9. In a lock, a body portion having a chamber adapted to receive a tumbler barrel, a shackle operatively disposed relative to said body portion, a bolt slidably mounted in said body portion and adapted to engage one end of said shackle, a barrel portion adapted to fit into said body portion, said barrel portion having an inwardly projecting sleeve, notched tumbler disks mounted in said barrel portion on said sleeve, a dial member superimposed on the outer face of said barrel portion, a spindle projecting from said dial portion and extending

through the sleeve of said barrel portion, a dial tumbler having a notch in the periphery thereof and provided with an axial opening to take over the dial spindle, said axial opening being in communication with diametrically opposed recesses in said tumbler, a pin projecting through said dial spindle, the ends of said pin coöoperating with the recessed portion of said dial tumbler whereby the tumbler will be rotated upon the turning of the dial, and means whereby rotation of said dial tumbler will result in selective rotation of said tumbler disks.

10. A lock comprising a body portion, a barrel portion adapted to be fitted in said body portion, a plurality of tumbler disks carried by said barrel portion, a shackle member and a plug member adapted to be inserted in the body portion, a bolt member carried by said body portion and adapted to be actuated by turning movement of the tumbler disks, the body portion and the barrel portion being so formed that when the shackle member and the plug member are inserted in the body the barrel and dial portions are securely held within said body portion.

11. In a lock, a body portion having a chamber adapted to receive a tumbler barrel, a tumbler barrel mounted in said central chamber, a shackle and a plug member mounted in said body portion, a sliding bolt operatively disposed in said body portion, a dial member superimposed upon said barrel portion, a spindle projecting from said dial member into said barrel portion, a plurality of tumbler disks mounted in said barrel portion, each of said tumbler disks being provided with a plurality of circumferentially arranged holes therethrough, a removable pin in one of said holes in each disk, and means connecting one of said disks to said dial spindle.

In testimony whereof I have hereunto set my hand in presence of two subscribing witnesses.

DAVID G. HARDY.
